(57) **CLAIM**

The ornamental design for a battery charger for X-ray digital imaging device, as shown and described.

DESCRIPTION

FIG. 1 is a top, front and left side perspective view of a battery charger for X-ray digital imaging device showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is an enlarged partial cross-sectional view of a portion taken along lines VIII-VIII of FIG. 2, in which internal structure thereof is omitted; and,

FIG. 9 is a top, front and left side perspective view thereof in a manner of use, to which an X-ray digital imaging device is connected.

The broken lines in FIGS. 3 and 9 depict environment that forms no part of the claimed design.
